UNITED STATES PATENT OFFICE.

JOHN B. DAVIDS, OF NEW YORK, N. Y.

BOTTLE-STOPPER.

SPECIFICATION forming part of Letters Patent No. 268,872, dated December 12, 1882.

Application filed February 16, 1882. (No model.)

To all whom it may concern:

Be it known that I, JOHN B. DAVIDS, of New York city, in the State of New York, have invented certain new and useful Improvements in Bottle-Stoppers, of which the following is a specification.

The object of the invention is to employ ordinary corks with the well-known advantages resulting from their use by providing convenient attachments, by which the same may be manipulated, combined with a shield or protector for the top of the cork.

I attach a ring, of proper size to allow a firm and strong engagement of the finger, by a 15 swivel-joint or hingewise to the eye or top of a helical wire which is screwed into the cork, its point being sharpened for this purpose. A sheet-metal disk or washer is placed round the helical wire, and lies between the eye 20 and the cork in which the wire is screwed. This washer strengthens the shank of the helical wire and protects the top of the cork. It gives the stopper a neat finished appearance, and affords a convenient means for displaying the name of the manufacturer, a trademark, or any desired design. Heretofore such attachments have been made to be used with a cork stopper, which consisted of the spiral screw for entering and taking hold of the cork, 25 and a loose ring attached to the top of the screw, so as to be turned down, as desired. I have improved upon this by combining with it the metal washer above described, which possesses the functions of strengthening 30 the wire protecting the top of the cork and affording a convenient medium for labeling.

The accompanying drawings form a part of this specification and illustrate what I consider the best means of carrying out the invention.

Figure 1 is a central section with the parts fully set in a cork, and the cork in a bottle with the ring folded down. Fig. 2 is a section 45 of the cork at right angles to Fig. 1 with the ring up, ready to receive a finger for withdrawing the cork. Fig. 3 shows the device in the

act of being inserted in a cork. Fig. 4 shows the device fully in place with the ring folded down. Fig. 5 is an end view with the ring 50 up.

Similar letters of reference indicate like parts in all the figures.

A is a bottle-cork of ordinary form, size, and texture.

B is a wire of steel or hard iron, formed spiral and sharpened for the ready and strong engagement with the cork A. Its upper or outer end is bent around in a small ring, B', and secured to form a complete and strong 60 eye.

C is my disk or washer, of sheet metal, stamped or otherwise treated in dies to decorate it, and fitted on the wire B below the eye, as shown. This disk C rests upon the top of 65 the cork when in position and protects it, while at the same time it strengthens the wire.

D is a strong continuous ring, engaged in the eye B', with liberty to turn therein.

I propose to manufacture the parts B C D, 70 properly engaged together, and supply them to be inserted in the corks A, as required.

M is a bottle-mouth, in which the cork is inserted. Sealing-wax may be applied, if desired, to better close the joint around the 75 cork. In forcing in the cork any amount of force applied by hand or by machinery will be distributed over a large surface on the cork by the washer C, and no injury can result. In the subsequent handling and packing of 80 the bottle the ring D is but little, if at all, in the way.

When it is desired to draw the cork, the ring D is extended up, as shown in Figs. 2 and 5, and affords a reliable hold, while the washer 85 C prevents the wire from being bent to one side or the other.

Modifications may be made in the proportions and form. The spiral or helix in the wire B may have three or more coils, instead 90 of two, as shown. The disk or washer C may be flat, as shown in Fig. 2 and the succeeding views, or dished, as shown in Fig. 1. The ring D may be a hollow ring made from sheet

metal, properly worked and requiring no soldering; but I prefer for general purposes solid wire bent around and joined by solder.

What I desire to claim as my invention

5 is—

The device for insertion in bottle-stoppers, herein described, consisting of the spiral B, having eye B', the loose ring D, and the sheet-metal plate C, the whole constructed, arranged, 10 combined, and adapted to serve as and for the purposes set forth.

In testimony whereof I have hereunto set my hand, at New York city, this 15th day of February, 1882, in the presence of two subscribing witnesses.

JOHN B. DAVIDS.

Witnesses:

CHARLES C. STETSON,
B. E. D. STAFFORD.
